United States Patent Office.

JACOB D. SPANG, OF DAYTON, OHIO.

Letters Patent No. 79,022, dated June 16, 1868.

IMPROVEMENT IN GAS-STOVES.

The Schedule referred to in these Letters Patent and making part of the same.

TO ALL WHOM IT MAY CONCERN:

Be it known that I, JACOB D. SPANG, of Dayton, in the county of Montgomery, and State of Ohio, have invented a new and improved Gas-Stove; and I do hereby declare that the following is a full, clear, and exact description of the construction and operation of the same, reference being had to the annexed drawings, making a part of this specification, in which—

Figure 1 is an end elevation.

Figure 2 is a top view.

Figure 3 is a longitudinal vertical section of the burner.

Figure 4 is a top view of the same.

The object of this invention is to construct a neat and convenient portable self-gas-generating stove, which can be easily kept in order and regulated, which is adapted to all the various purposes of cooking, heating, &c., and which utilizes the heat and the fuel to the greatest possible degree.

In the drawings, A represents the body of the stove, being an oblong metallic case, having a series of apertures, *a a a*, around its walls, and provided with a cover, A', which fits tightly upon it, the cover having an opening, *a'*, over each burner, to receive and support the various cooking-utensils that may be employed in connection with the stove.

B is the reservoir, which contains the gasoline, petroleum, or other substance from which the gas is to be generated, being provided with suitable ports, *b b*, through which it can be filled, and a pipe, *b'*, to conduct the gasoline towards the burners.

C is a pipe just outside of the rear wall of the stove, and lying in a horizontal position nearly parallel with it, as seen in fig. 2. At its centre it receives the pipe *b'* from the reservoir, and from different points along its inner wall, branch-pipes, *c c c c*, one to each burner, pass in through the wall of the stove, conducting the gasoline to the several burners. These branch-pipes pass in across the middle of the stove, then bend downward, then back to the middle, and then upward exactly under the apertures *a' a'*, where they are provided with suitable burners, and where the gas, after being manufactured, is consumed. The burners are, by this arrangement, directly under the horizontal portion of the pipes, and, as the gasoline passes through the branch-pipes, arriving at the point above the burners, it is vaporized, and only the vapor passes over to the burners. The heat of the burning gas of the stove therefore serves to reduce the petroleum to gas, and the stove thus makes its own gas and supplies itself with fuel.

Directly under the burners are hemispherical depressions, D D, in the bottom of the stove, the walls of which are perforated, as seen at *e e e*, in order to provide a constant supply of fresh air to the burners above, the object being not only to supply them with air to keep up combustion, but to introduce the air in such a direction that it shall be heated by the burner, and then be thrown directly upward against the cooking-vessels. From them it is deflected to the sides of the stove, and escapes at last through the apertures *a a a*, serving to warm the room where the stove is situated.

In connection with this arrangement, I also provide deflectors, G, hinged by short arms to the upper side of the pipes *c c* above the burners, and in the form of circular plates radially corrugated, by which the heated air will be more effectually thrown away from a focus over the burner, and allowed to rise around the bottom of the pot or other cooking-utensil.

Suitable stop-cocks, *i i*, are provided for each branch-pipe, being affixed outside of the stove, by which the supply of fuel may be shut off from any or all of the burners at once, if desired, and in addition to these, another, *i'*, by which the supply to all the burners may be instantly cut off whenever it is necessary. By means of these various cocks, the fires may be regulated with the utmost possible nicety.

The burners which I employ are clearly shown in figs. 3 and 4, each burner being constructed of two pieces, *m n*, the former screwed to the end of the pipe *c* in the usual manner, and the latter screwed upon the end of the former, as shown in fig. 3. The piece, *m*, has but a single hole in it, and that at the centre, opening into

a chamber, o , within the piece n , when the latter is in position. The piece, n , is provided with several holes, $v v v$, arranged around a central hole in its top, as clearly seen in fig. 4, and serving to throw jets of gas at different inclinations from the vertical jet thrown by the central hole. This burner can be readily taken off to be cleansed, when required, and, if but a single jet is needed, the upper cap n may be removed. The burner has been tested by a long course of practical experiment and use, and is found to be much superior to the old burners for use in connection with gas and vapor-burning stoves.

The whole stove, thus constructed, can be supported upon any kind of pedestal F . It will need no chimney or flue; it can be set in any part of the building where it is most convenient for the time being to use it, and can be readily moved from one place to another, as convenience may suggest. It is neat and ornamental in appearance, and can be made at less expense than any other stove used for a similar purpose.

Having thus described my invention, what I claim as new, and desire to secure by Letters Patent, is—

The burner, consisting essentially of the parts $m n$, constructed as described, and operating in the manner and for the purpose set forth.

J. D. SPANG.
